MOISTENING MEANS FOR DUPLICATORS

Alfred Marchev, La Grange, Ill., assignor to
Ditto, Incorporated, Chicago, Ill., a corpora-
tion of West Virginia

Application February 8, 1937, Serial No. 124,713

13 Claims. (Cl. 101—132)

The invention relates to moistening means for duplicators and is particularly adapted to be embodied in a duplicating machine of the type wherein the copy sheets are moistened with a solvent which will dissolve the ink upon a master sheet, the moistened copy sheets being brought into contact with the master sheet so that the data printed or written upon the master sheet will be transferred to the copy sheets. A relatively large number of copies may be made in this manner from a single master sheet.

A primary object of the invention is to provide means for supplying a relatively large amount of solvent quickly to the moistening means when the moistening means are first set in operation or have become dry for some reason or other.

One advantage of the improved moistening means is that when it is embodied in a duplicating machine of the kind described, it is unnecessary to waste a number of copy sheets when the machine is first used after it has been standing idle for some time. The improved moistening means insures that the first copy sheets passing through the machine will be sufficiently moistened to dissolve the ink of the data upon the master sheet. Of course, the ink is dissolved gradually as the copy sheets carry very little solvent.

Other objects and advantages will become apparent as the following detailed description progresses, reference being had to the accompanying drawings, wherein—

Fig. 1 is a side elevation, partly broken away, of a duplicating machine which embodies the invention.

Fig. 2 is a fragmentary plan section taken on line 2—2 of Fig. 1, certain parts of the apparatus being broken away to illustrate the construction thereof.

Fig. 3 is a section taken on line 3—3 of Fig. 2.

Fig. 4 is a fragmentary section taken substantially on the same line as Fig. 3.

Fig. 5 is a vertical transverse section taken on line 5—5 of Fig. 3, and

Fig. 6 is a section taken on line 6—6 of Fig. 5.

Referring to the drawings wherein a preferred embodiment of the invention is illustrated, the reference characters 10 and 11 designate generally two side frames which are secured to each other by means including a sheet metal bracket 13 extending between the forward ends of the side frames 10 and 11 (Figs. 1 and 3). Rotatably journalled between the side frames 10 and 11 is a hollow duplicating drum 14 having a slot 15

in its cylindrical wall. Clamping fingers 17 pivotally mounted within the drum 14 by suitable means (not shown) project through the slot 15 and are adapted to clamp the forward edge of a master sheet 18 upon the cylindrical surface of the drum 14.

The master sheet 18 is preferably prepared by placing it upon the carbon side of a carbon sheet and then writing or typewriting upon the exposed surface of the master sheet so that the data will appear in reverse upon the side contacting the carbon sheet. When the copy sheets are advanced through the improved machine, the surfaces that will come in contact with the reverse writing or typewriting upon the master sheet are moistened with a solvent for the carbon so that as each copy sheet contacts a master sheet, the carbon will be moistened and the data will be duplicated on the copy sheet.

Co-operating with the duplicating roller 14 to 20 press the copy sheets against the master sheet 18, is a platen roller 20. Disposed in front of the platen roller 20 is a roller 21 which co-operates with a roller 22 to feed copy sheets to the duplicating drum 14 and platen roller 20. The roller 22 is preferably non-absorbent and is mounted on a shaft 23. The roller 21 is also preferably non-absorbent and is mounted on a shaft 24. The surface of the roller 21 is preferably provided with a plurality of annular grooves 25 to 30 insure rapid evaporation of any excess solvent which gathers on the surface of the roller 21. The roller 21 is urged yieldingly against the roller 22 by means comprising pivoted levers 27 and springs 28.

The improved machine preferably comprises a table 30 upon which a stack of copy sheets may be placed so that the operator may feed them one by one to the rollers 21 and 22. It will be noted that the end of table 30 adjacent the rollers 21 and 22 is bent upwardly to bring the forward edges of the copy sheets into registry with the rollers.

A container 33 for holding a supply of solvent is mounted between the forward ends of the side frames 10 and 11 and is provided with pumps 34 and 34a which are actuated by a lever 35 pivoted upon a stub shaft 36 and actuated, in turn, by a lever 37 also pivoted on the shaft 36. One end of the lever 37 engages the bottom surface of the lever 35, the other end of the lever 37 being provided with a roller 38 which rides upon a cam 39 which is substantially cylindrical but has a relatively deep notch 40 in its periphery. A spring 41 disposed between the lever 37

and a bracket 42 yieldingly urges the roller against the periphery of the cam 39 and causes it to drop into the recess or notch 40 whenever the notch comes into registry with the roller. 5 The cam 39 is constrained to rotate in unison with the duplicating drum 14. Obviously, when the cam 39 rotates through a plurality of revolutions, the lever 37 is displaced angularly by the combined action of the spring 41 and the cam 39 so that for each revolution of the cam 39 the lever 37 first displaces the lever 35 in a clockwise direction (Fig. 1) and then permits it to return to the position wherein it is shown in Fig. 1. The lever 35 actuates the pumps in 10 a manner hereinafter described.

15 The pumps 34 and 34a are preferably of identical construction and therefore it will only be necessary to describe the pump 34 in detail. As best shown in Fig. 3, the pump 34 comprises a cylinder 40d which extends through the container 33 and is provided with a central bore 41d having ports 42d through which the bore 41d communicates with the lower portion of the container 33. Ports 44 permit the bore 41d to communicate with the upper portion of the container 20 33. Extending into the bore 41d from the upper end thereof is a piston rod 46 having a piston 47 at its lower end. It will be noted that the upper end of the piston rod 46 is slidably journaled in a closure member 58 at the upper end of the bore 41d. Extending between the closure member 58 and the piston 47 is a compression spring 51 disposed around the piston rod 46, the construction being such that the spring 51 yieldingly urges 25 the piston 47 toward the bottom of the bore 41d. At the lower end of the bore 41d and below the container 33, the cylinder 40d is provided with a port 53 through which the bore 41d communicates with a tube 54 which has its outer end turned upwardly as shown at 55. The turned up end of the tube 54 acts as a seat for a ball valve 56 yieldingly urged against the seat by a spring 57. This construction provides a check valve which permits solvent to flow from the bore 41d 30 through the tube 54 but prevents the solvent from returning through the tube 54. The ball valve 56 is disposed in a housing 58 secured to the turned up end of the tube 54. The housing 58 is connected by a rubber tube 60, or the equivalent, to a horizontally extending pipe 61 for a 35 purpose hereinafter described.

40 As stated above, the pump 34a is substantially identical in construction with the pump 34 and is adapted to discharge solvent through the tube 54a which corresponds to the tube 54 described above. The tube 54a terminates in a check valve 56a which is preferably identical with the check valve described in connection with the tube 54. The tube 54a communicates with a flexible tube 60a, or the equivalent, through the check valve 56a. The upper end of the flexible tube 60a is connected to a metallic tube 70.

45 As best shown in Figs. 2 and 3, the free end of the lever 35 is provided with a handle portion 71 whereby the lever may be oscillated manually. Bracket members 72 and 73 riveted to the lever 35 intermediate its ends have their forward ends disposed adjacent the upper end of the piston rod 46 and the upper end of the corresponding piston rod 46a of the pump 34a. Nuts 75 and 75a at the upper ends of the piston rods 46 and 46a, respectively, are engageable by the forward ends of the bracket members 73 and 72, respectively. Obviously, when the lever 35 is displaced in a clockwise direction (Fig. 3), the pistons 47 will be ele-

5 vated in the bore 41d and the corresponding bore of the pump 34a against the action of the spring 51 and the action of the corresponding spring in the pump 34a and when the lever 35 returns to the position wherein it is shown in Fig. 3, the spring 51 and the corresponding spring in the pump 34a will urge the pistons of the two pumps downwardly. When the pistons are in their uppermost positions, the solvent will flow into the lower ends of the bores in the pumps through the ports 42 and the corresponding ports in the pump 34a. When the spring 51 and the corresponding spring in the pump 34a urge the pistons downwardly, the solvent is driven outwardly through the tubes 54 and 54a to the flexible tubes 60 and 60a.

10 It will be noted that the tube 61 extends through the upper portion of a container or receptacle 80 disposed adjacent the roller 22, the receptacle 80 being open at its top and being provided with a pivoted closure member 81. The receptacle 80 15 comprises front and back walls 82 and 83, respectively, and a bottom wall 84. Extending through a slot 85 provided in the back wall 83 is a strip or pad of felt 86, the outer end of which is in contact with the lower end of a pad or strip of felt 87 secured to the outer side of the back wall 83 by means comprising a plate 88 and screws 89. The upper and lower ends of the felt strip 87 are beveled as at 90. The purpose of this construction is to permit the felt strip 87 to be reversed 20 when that part of it now at the bottom becomes worn. The lower end of the strip 87 contacts the roller 22.

25 The tube 70 to which the flexible tube 60a is connected, extends into the receptacle 80 and terminates in a valve housing 101. A valve device 102 disposed in the housing 101 controls the flow of solvent from the tube 70 to tubes 104 and 105 extending in opposite directions from the valve housing 101 adjacent the inner end of the felt strip 30 86, the tubes 104 and 105 being provided with a plurality of apertures 106 through which solvent may flow and drop upon the inner end of the felt strip 86. The receptacle 80, the housing 101, the valve device 102 and the tubes 104 and 105 35 are described in detail in the co-pending application, Serial No. 58,522 filed January 10, 1936, by Stephen Kokay. The details of construction of the enumerated parts do not form a part of this invention and therefore need not be described in detail in the present disclosure.

40 If an excess of solvent is delivered to the felt strip 86, it flows into the lower portion of the receptacle 80 and out through a nipple 108 which is connected by a flexible tube 109, to a nipple 110 45 extending upwardly from the reservoir 33 and opening into it.

45 The receptacle 80 is pivotally mounted between the side frames 10 and 11 by means comprising pins 112 and 113 and more fully shown and described in the co-pending application, Serial No. 58,522. It may be mentioned that a spring 116 (Figs. 2 and 6) yieldingly tends to rotate the receptacle 80 in a counter-clockwise direction (Fig. 3) to keep the lower end of the felt strip 60 55 86 in contact with the roller 22. It is understood, of course, that the solvent delivered to the felt strip 86 passes through the strip into the lower end of the felt strip 87 which, in turn, applies the solvent to the roller 22.

50 The tube 61, which has one end communicating with the upper end of the flexible tube 60, extends through and is pivotally journaled in the end walls of the receptacle 80. The other end of the tube 61 is closed.

Fixed to and suspended from the tube 61 is a trough 115 having a curved bottom wall 116 and end walls 118. The tube 61 extends through the end walls 118 and is secured thereto so that angular displacement of the tube 61 around its longitudinal axis will be accompanied by similar angular displacement of the trough 115. The tube 61 is provided with a plurality of apertures 120 through which solvent may be discharged from the tube into the trough.

Projecting through one of the walls 118 is a nipple 122, to the outer end of which one end of a rubber tube 123 is secured, the other end of the rubber tube 123 being secured to one end 15 of a nipple 125 projecting through one of the end walls of the receptacle 80 (Fig. 5). One end of a rubber tube 127 is secured to the outer end of the nipple 125, the other end of the rubber tube 127 being secured to the outer end of a nipple 129 which projects from the reservoir 33 and communicates therewith. It will be noted that when the trough 115 is in the position wherein it is shown in Fig. 3, the nipple 122 is in a position wherein it permits the trough to become 20 nearly filled with solvent before this solvent will drain through the nipple 122, the tube 123, the nipple 125, the tube 127 and thence through the nipple 129 into the reservoir 33. As the tube 123 is flexible it is obvious that the trough 115 25 may be tipped from the position wherein it is shown in Fig. 3 to the position wherein it is shown in Fig. 4 so that the contents of the trough will be dumped upon the felt strip 86. The means for tipping the trough 115 comprises 30 a pin 130 projecting from a collar 131 fixed to one end of the tube 61. Obviously, the operator of the machine may angularly displace the pin 130 to tip the trough 115 and to return it to the position wherein it is shown in Fig. 3.

Means is preferably provided for controlling the amount of solvent dumped from the reservoir 33 to the receptacle 80 and the trough 115. This means comprises an extension 135 on the bracket 72, which extension 135 carries a roller 45 136 riding upon a cam 137 fixed to a shaft 138 journaled in the side frame 10. At its outer end the shaft 138 is provided with a knob 140 whereby it may be rotated. When the roller 136 and the cam 137 are in the positions wherein they are 50 illustrated in Fig. 3, the lever 35 rests upon one end of the lever 37 whenever the roller 38 is in the notch 40 of the cam 39. This insures that a maximum stroke of the pistons in the pumps 34 and 34a will be obtained during the operation 55 of the machine. However, if the knob 140 is rotated in a clockwise direction (Fig. 1) so as to raise the roller 136, the lever 35 will be displaced angularly a corresponding distance so that it will not rest upon the left hand end (Fig. 3) 60 of the lever 37 when the roller 38 is in the notch 40. Obviously, when the machine is operated after such adjustment, the lever 35 will be displaced through a smaller angle during each revolution of the cam 39 and the pumps 34 and 34a 65 will then deliver a smaller quantity of solvent to the receptacle 80 and the trough 115.

It may be mentioned that the valve 102 may be adjusted to deliver unequal quantities of solvent to the pipes 104 and 105 and may also be 70 adjusted to deliver all of the solvent to one of these pipes and none to the other.

As best shown in Fig. 3, an arcuate shield 145 extends between the roller 22 and the duplicating drum 14, the shield being secured to the side 75 frames 10 and 11. This shield prevents the tail

ends of the master sheets from engaging the roller 22 during rotation of the duplicating drum.

The platen roller 20 is mounted in ball bearings 150 carried by pivoted levers 151 which have means including a bolt 153 for adjusting the pressure with which the platen roller 20 abuts against the duplicating drum 14.

In the present instance, the improved machine is operated manually and for this purpose is provided with a crank 158 with which a pinion 159 is constrained to rotate. The pinion 159 meshes with a gear 160 with which the duplicating drum 14 is constrained to rotate. A larger gear 162 constrained to rotate with the duplicating drum 14 meshes with a pinion 163 and the pinion 163 15 meshes, in turn, with a pinion 164. The shaft 23 to which the roller 22 is fixed is driven by the pinion 164, the pinion 164 being mounted on that shaft. The roller 21 is rotated as a result of its frictional engagement with the roller 22. 20

The platen roller 20 frictionally engages the duplicating drum 14 and is rotated thereby in synchronism therewith.

The improved duplicating machine operates substantially as follows: A master sheet 18 is 25 fixed to the duplicating drum by means of the clamping fingers 17. The copy sheets are placed upon the table 30 and while the machine is being driven through the crank 158, the copy sheets are advanced one at a time to the feed rollers 30 21 and 22. The feeding of the copy sheets is done each time the roller 38 engages the notch 40 in the cam 39, it being very evident to the operator each time the roller 39 drops into the notch 40. When copy sheets are advanced to 35 the feeding rollers 21 and 22 while the roller 38 is resting in the notch 40, the further rotation of the crank 158 will cause the feed rollers 21 and 22 to advance the copy sheet in synchronism with the duplicating drum 14 so that the copy 40 sheet will register with the master sheet. During the operation of the machine, solvent is distributed upon the roller 22 by the felt strip 87 which receives the solvent from the felt strip 86. As the copy sheets pass between the rollers 45 21 and 22, the upper surfaces thereof are covered with a thin film of solvent which dissolves the ink or coloring matter upon the master sheet to a sufficient extent to insure that impressions there-of will appear on the copy sheets. After the 50 machine has been operated for a relatively short period of time, and assuming that the cam 137 has been adjusted properly to regulate the amount of solvent pumped by the pump 34a, the pump 34a will deliver a substantially constant 55 quantity of solvent to the tube 70 through the flexible tube 60a and the valve 102 will distribute it to the tubes 104 and 105 as desired. The solvent will flow through the apertures 106 and fall upon the felt strip 86 and the felt strip 86 will 60 supply a sufficient quantity of solvent to the felt strip 87 to insure that a sufficient quantity of solvent will be supplied to the roller 22 to moisten the copy sheets properly. Any excess of solvent delivered to the receptacle 80 by the tube 70 will 65 pass through the felt strip 86 and drain back to the reservoir 33 through the tube 109. Of course, as soon as the machine is in operation and the pump 34a is delivering solvent to the tube 70, the pump 34 will be delivering solvent to the tube 70 70 and the solvent will accumulate in the trough 115 until it has reached the level permitted by the nipple 122 and the tube 123. After having reached this level, all excess solvent delivered to the trough 115 drains through the nipple 122, the 75

tube 123, the nipple 125 and thence through the tube 121 to the reservoir 33.

If, after the machine has been operated for some time, it is permitted to remain idle until 5 the solvent has evaporated from the portions of the felt strips 86 and 87 exposed to the atmosphere, the trough 115 may be tipped so that the solvent which has accumulated therein will be dumped upon the felt strip 86 and a sufficient 10 quantity of it will pass into the lower end of the felt strip 87 so that it will moisten immediately the roller 22 when the machine is again set in operation. It will be noted that the slot 85 is somewhat wider than the thickness of the felt 15 strip 86 and therefore when the contents of the trough 115 are dumped onto the felt strip 86, some of the solvent will flow directly to the felt strip 87 through the slot 85.

If the machine has not been used for some 20 time and the trough 115 is empty, the operator may oscillate the lever 35 before the machine is set in operation and pump sufficient solvent to the receptacle 80 to cause the strips 86 and 87 to become properly moistened so that the lower end 25 of the strip 87 will moisten the roller 22 when the machine is set in operation.

While I have shown and described certain embodiments of my invention, it is to be understood that it is capable of many modifications. 30 Changes, therefore, in the construction and arrangement may be made without departing from the spirit and scope of the invention as disclosed in the appended claims, in which it is my intention to claim all novelty inherent in my invention as broadly as permissible, in view of the prior art.

I claim:

1. In a duplicating machine, means for pressing copy sheets against a master sheet having data imprinted thereon with ink, a roller engageable with said copy sheets to apply thereto a solvent for said ink, a receptacle adjacent said roller, fibrous material projecting from said receptacle to deliver solvent to said roller, means 40 for delivering solvent to said receptacle to supply it to said fibrous material, a second receptacle disposed within the first mentioned receptacle, means for delivering solvent to said second receptacle, and means for discharging the contents of said second receptacle on said fibrous material.

2. In a duplicating machine, means for pressing copy sheets against a master sheet having data imprinted thereon with ink, a roller for moistening the copy sheets with a solvent for 55 said ink, a receptacle disposed adjacent said roller, fibrous material projecting from said receptacle and engaging said roller to supply the solvent thereto, a second receptacle mounted 60 within the first mentioned receptacle, means for discharging the contents of said second receptacle on said fibrous material, a reservoir for said solvent, means for pumping solvent from said reservoir to the first mentioned receptacle to supply solvent to said fibrous material, and means 65 for pumping solvent to said fibrous material, and means for pumping solvent from said reservoir to said second receptacle.

3. In a duplicating machine, means for pressing copy sheets against a master sheet having data imprinted thereon with ink, a roller for 70 moistening the copy sheets with a solvent for said ink, a receptacle disposed adjacent said roller, fibrous material projecting from said receptacle and engaging said roller to supply the solvent thereto, a second receptacle mounted within the 75

first mentioned receptacle, means for discharging the contents of said second receptacle on said fibrous material, a reservoir for said solvent, means for pumping solvent from said reservoir to the first mentioned receptacle to supply solvent 5 to said fibrous material, means for pumping solvent from said reservoir to said second receptacle, and a second roller for pressing said copy sheets against the first mentioned roller.

4. In a duplicating machine, a duplicating 10 drum, means for securing a master sheet to said drum, a pressure roller co-operating with said drum to press copy sheets against said master sheet, a pair of rollers for feeding copy sheets to said duplicating drum and pressure roller, one of 15 said feeding rollers engaging said copy sheets to apply a solvent thereto, a receptacle adjacent said rollers, fibrous material projecting from said receptacle and engaging said solvent-applying roller to supply solvent thereon, means for delivering 20 solvent to said receptacle to supply said fibrous material with it, a second receptacle pivotally mounted in the first mentioned receptacle, said second receptacle being movable into a position wherein its contents will be discharged on said 25 fibrous material, and means for delivering solvent to said second receptacle.

5. Apparatus for moistening a sheet of paper, or the like, said apparatus comprising a roller engageable with the paper, fibrous material for 30 supplying liquid to the roller, means normally supplying liquid to said fibrous material and normally keeping the fibrous material saturated with the liquid, and manually controlled auxiliary means for supplying a large quantity of liquid to 35 said fibrous material in a short period of time when said fibrous material is dry whereby said fibrous material will become saturated with said liquid in a short interval of time.

6. Apparatus for moistening a sheet of paper, 40 or the like, said apparatus comprising a roller engageable with the paper, fibrous material for supplying liquid to the roller, a reservoir for the liquid, means normally pumping said liquid to said fibrous material to keep it saturated there- 45 with, and manually controlled means supplied with said liquid by said pumping means and adapted to supply an additional quantity of liquid to said fibrous material when it is dry whereby said fibrous material will become saturated with 50 said liquid in a short interval of time.

7. Apparatus for moistening a sheet of paper, or the like, said apparatus comprising a roller engageable with the paper, fibrous material for supplying liquid to the roller, a reservoir for the 55 liquid from which said fibrous material is supplied with the liquid, means supplied with liquid from said reservoir and adapted to store a quantity of it, and means for causing said storing means to discharge said liquid on said fibrous material 60 whereby said fibrous material will become saturated with said liquid in a short interval of time.

8. Apparatus for moistening a sheet of paper, or the like, said apparatus including fibrous material through which the moistening liquid passes, 65 a reservoir from which liquid is supplied to said fibrous material, means supplied with said liquid from said reservoir and adapted to store a quantity of it, and manually operable means for causing said storing means to discharge said stored liquid on said fibrous material whereby said fibrous material will become saturated with said liquid in a short interval of time.

9. Apparatus for moistening a sheet of paper, or the like, said apparatus comprising a roller en- 75

gageable with said sheet of paper to apply the liquid thereto, a receptacle adjacent said roller, fibrous material projecting from said receptacle to deliver liquid to said roller, means for delivering liquid to said receptacle to supply it to said fibrous material, a second receptacle disposed within the first-mentioned receptacle, means for delivering liquid to said second receptacle, and means for discharging the contents of said second 5 receptacle on said fibrous material.

10. Apparatus for moistening a sheet of paper, or the like, said apparatus comprising a roller engageable with said sheet of paper to apply the liquid thereto, a receptacle adjacent said roller, fibrous material projecting from said receptacle to deliver liquid to said roller, means for delivering liquid to said receptacle to supply it to said 15 fibrous material, a second receptacle disposed above said fibrous material, means for delivering liquid to said second receptacle, and means for discharging the contents of said second receptacle on said fibrous material in a short period of time whereby said fibrous material will become saturated quickly with said liquid.

20 11. In a duplicating machine, means for pressing copy sheets against a master sheet, means including fibrous material for moistening the copy sheets with a solvent, a receptacle for said solvent, means for delivering solvent to said fibrous material from said receptacle, and a second means 25

30

manually controlled for delivering solvent to said fibrous material from said receptacle and having greatly increased capacity for rapid delivery of solvent to said fibrous material as compared with said first named solvent delivery means.

12. In a duplicating machine, means for pressing copy sheets against a master sheet having data imprinted thereon with ink, a roller for moistening the copy sheets with a solvent for said ink, fibrous material engaging said roller to supply the solvent thereto, a reservoir for said solvent, means for pumping solvent from said reservoir to said fibrous material, a container, means for pumping solvent from said reservoir to said container, and means for discharging the contents of said container on said fibrous material. 10

13. In a duplicating machine, means for pressing copy sheets against a master sheet having data imprinted thereon with ink, a roller for moistening the copy sheets with a solvent for said ink, fibrous material engaging said roller to supply the solvent thereto, a reservoir for said solvent, means for pumping solvent from said reservoir to said fibrous material, a container, means for pumping solvent from said reservoir to said container, means for discharging the contents of said container on said fibrous material, and a second roller for pressing said copy sheets against the first mentioned roller. 15 20 25

ALFRED MARCHEV. 30
